(57) **CLAIM**

The ornamental design for a structural gap filler, as shown and described.

DESCRIPTION

FIG. 1 is a perspective view of a structural gap filler showing our new design;

FIG. 2 is a right side view thereof, the left side view being a mirror image thereof;

FIG. 3 is a top view thereof;

FIG. 4 is a bottom view thereof;

FIG. 5 is a front view thereof; and,

FIG. 6 is a rear view thereof.

The structural gap filler is shown with a symbolic break in its length. The appearance of any portion of the structural gap filler between the break lines forms no part of the claimed design.
